US0D1012093S

(12) **United States Design Patent** (10) **Patent No.:** **US D1,012,093 S**
(45) **Date of Patent:** **** Jan. 23, 2024**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Mani Amini**, San Jose, CA (US);
Patrick Lee Coffman, San Francisco, CA (US); **Aurelio Guzmán**, San Francisco, CA (US); **Raymond Sepulveda**, San Jose, CA (US); **Chun Kin Minor Wong**, Cupertino, CA (US)

(73) Assignee: **Apple Inc.**, Cupertino, CA (US)

(**) Term: **15 Years**

(21) Appl. No.: **29/757,195**

(22) Filed: **Nov. 4, 2020**

Related U.S. Application Data

(63) Continuation of application No. 29/649,913, filed on Jun. 3, 2018, now Pat. No. Des. 904,449.

(57) **CLAIM**

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof, and form no part of the claimed design.

The broken white lines within the peripheral dashed broken lines form no part of the claimed design.

1 Claim, 1 Drawing Sheet
